ELECTRICAL TEST CLIP

Clifton C. Wright, Chicago, Ill., assignor to Rapid Specialties Company, a corporation of Illinois

Application December 1, 1944, Serial No. 566,152

3 Claims. (Cl. 173—273)

1

In the manufacture of electrical apparatus, equipment or products a great deal of testing must be done, requiring apparatuses or devices to be connected in a circuit containing an electric meter. Little clips are commonly used in making such connections. Although a great variety of such clips are available, I know of none which is not open to some serious objection such, for example, as being time wasting, requiring too much attention on the part of the user, having only a limited field of usefulness so that it may be necessary to pick up several before the right one is found, getting out of order easily and being difficult to restore to a satisfactory working condition when they need it.

The object of the present invention is to produce a simple and novel clip free from all of the faults and limitations inherent in prior devices, especially those just mentioned.

The various features of novelty whereby my invention is characterized will hereinafter be pointed out with particularity in the claims; but, for a full understanding of the invention and of its objects and advantages, reference may be had to the following detailed description taken in connection with the accompanying drawing, wherein:

Figures 1, 2 and 3 are, respectively, a side view, an edge view and a top plan view of a preferred form of my device; Fig. 4 is a section on line 4—4 of Fig. 1; Fig. 5 is a section on line 5—5 of Fig. 4; Fig. 6 is an elevational view of one of the contact pieces or fingers; and Fig. 7 is an elevational view of the leaf spring that holds the contact pieces yieldingly in face to face engagement with each other.

Referring to the drawing, 1 and 2 are a pair of contact pieces or fingers composed of flat strips of metal adapted normally to lie face to face, in contact with each other. At one end the pieces are curved outwardly, away from each other, as indicated at 3, to provide a flaring mouth into which a wire or a blade-like terminal may be inserted. These contact pieces are connected together at the other end by a hinge joint to permit relative rocking movements in the direction to shift their free ends toward and away from each other. The hinge joint is preferably of a special type to permit relative bodily movements of the hinge ends of the contact pieces from and toward each other and complete separation thereof, when desired. In the arrangement shown, the hinge joint comprises a socket 4 in the inner or under face of member 2 and a small projection 5

2

on the adjacent face of member 1; the projection being loosely entered in the socket.

The contact piece 1 is provided with a headed stud 6 fixed thereto between the ends of the piece, preferably nearer the hinge end than the other, and extending through a hole 7 in contact piece 2; the stud being much longer than the thickness of the latter contact piece. Engaged with the outer face of and extending lengthwise of member 10 2 is a bow shaped leaf spring 8 through a hole 9 at the middle of which the stud passes; the spring being under an initial stress so that the ends thereof thrust against the outer face of member 2 while its middle portion presses outwardly 15 against the head on the stud. The spring contains at the hinge end of the device a small hole 10 into which a little pin or projection 11 on the contact piece extends.

The holes 7 and 9 are preferably as wide as the 20 diameter of the stud and somewhat longer in the direction of the length of the contact piece; an elongation of about ten thousandths of an inch being usually sufficient. Likewise, the hole 10 in the spring is a little longer, in the direction of the 25 length of the spring than the diameter of the pin or projection 11 that cooperates with this hole.

The pins 5 and 11 are preferably integral parts 30 of members 1 and 2, respectively, formed by applying pressure against one side of each member to create a socket and to cause the metal displaced in the making of the socket to protrude beyond the other side or face as a pin or projection. Thus the socket 4 and the pin or projection 11 are the result of a single pressing operation.

The contact piece 1 is provided at the hinge end with an extension 12 that is bent laterally at right angles to form a foot or base. The part 12 contains a hole 13 through which a terminal element or binding post on a meter may be slipped; 40 so that, upon applying the usual nut to such element, the clip is mechanically and electrically connected to the meter. Or, if necessary or desirable, the clip may be fastened to a bench or other support by means of a screw engaged in hole 13; and, if a wire has previously been inserted beneath the foot or base 12, an electrically conductive connection between the same and the clip will be established simultaneously with the securing of the clip to the support.

In using the clip, the wire or other terminal element is simply pressed down between and below the diverging ends 3 of the members 1 and 2, and is afterwards simply pulled out again upon the completion of the test being made; there being no need to spread the contact pieces apart

before the wire or terminal is inserted. In the case of a stiff element, such as a blade or a heavy wire, only one hand need be used to insert it in the clip. On the other hand, a fine wire must be held in both hands to attach it.

Because of the loose connections between the two contact pieces or fingers, they will grip a fine wire or a heavy wire equally well, both from the standpoint of a mechanical fastening and that of a good electrically conductive connection. I have used the same clip with very fine wires and with wires one eighth of an inch thick.

If the strength of the spring diminishes objectionably after prolonged use, the fault can be corrected quickly and easily. The lower end of the spring may be lifted off the projection 11 and the spring be swung about the stud 6 as an axis into a position transverse to the contact pieces. While in this new position the spring may be bent to a sharper curvature so that, upon restoring it to its original, normal working position, it exerts a greater pressure on the contact pieces than before.

It will also be seen that after the spring has been unlatched and turned crosswise of the contact pieces, the member 2 can be lifted clear of the pin or projection 5 and then be turned so as to lie crosswise of the cooperating member 1. By this means the cooperating faces on the two contact pieces are exposed so that they can be easily cleaned and be in perfect working order when the parts of the clip are restored to their working positions relative to each other.

While I have illustrated and described with particularity only a single preferred embodiment of my invention, I do not desire to be limited to the exact details thus illustrated and described; but intend to cover all forms and arrangements coming within the definitions of my invention constituting the appended claims.

I claim:

1. A device of the character described, comprising two contact pieces lying flat against each other and flaring away from each other for a short distance inwardly from one end, a projection on one of said pieces at the other end entered loosely in a socket in the second piece, a headed stud extending loosely through the second piece between the ends of the device and permanently fixed to the first piece, the parts being so proportioned that when said projection is lifted out

of the socket the contact pieces may be turned about the axis of the stud so as to lie crosswise of each other, and a bowed leaf spring underneath the head on the stud extending lengthwise of and bearing at its ends on said second piece to hold it yieldingly against the other piece, the spring being turnable on the stud to position it crosswise of said contact pieces.

2. A device such as set forth in claim 1, where-
10 in there is an interlock between one end of the spring and the contact piece against which it bears and which can be undone by raising that end of the spring a predetermined distance from the surface of the contact piece which it engages.

15 3. A device of the character described, comprising two contact pieces lying flat against each other and flaring away from each other for a short distance inwardly from one end, a projection on one of said pieces at the other end entered loosely in a socket in the second piece to produce a hinge-like connection, a headed stud extending loosely through said second piece between the ends of the device and fixed to the first piece, a bowed leaf spring underneath the head on the stud extending lengthwise of and bearing 20 at its ends on said second piece to hold it yieldingly against the other piece, said spring being turnable to position it crosswise of the contact pieces and having a small hole therein in the vicinity of that end of the second contact piece containing the socket, and said second piece having a short projection entered loosely in said small hole in the spring to hold it normally against turning.
